UNITED STATES PATENT OFFICE

2,615,118

RAISING AND LOWERING FACILITIES FOR
DEEP WELL COOKER HEATERSWilliam D. Kelly, Western Springs, Ill., assignor
to Tuttle & Kift, Inc., Chicago, Ill., a corpora-
tion of Illinois

Application April 16, 1949, Serial No. 87,875

1 Claim. (Cl. 219—37)

1

My invention relates to a deep well cooker of the type wherein a heater is located at the bottom of the well for heating the contents of a pot or kettle placed in the well, and has reference more particularly to facilities for elevationally adjusting the heater.

Such deep well cookers are commonly used in ranges, especially electric ranges, and are usually made as a part of the range, with the well extending downwardly from the range top into the interior of the range. For deep well cooking, the heater is located at the bottom of the well, but experience has demonstrated that it is desirable, at times, to locate the heater at the top of the well so that it may be used as an ordinary surface heater.

However, as the well is enclosed in the range and the heater is accessible only from the top of the well, considerable difficulty has been experienced heretofore in providing satisfactory facilities for raising and lowering the heater. In Rutenber Patent No. 2,416,645, for example, a special tool is provided to reach down in the well and engage the heater for raising and lowering the heater.

With my invention, no such tool is required, as the well itself is constructed with facilities, operatively accessible at the top of the well, above the range top, whereby the heater is readily adjustable from the normal position at the bottom of the well to a position at the top of the well where it may be employed as an ordinary surface heater.

My heater adjusting facilities also provide for positioning of the heater at one or more selected elevations between the extreme bottom and top positions of adjustment thereof.

The principal objects of my invention are, to provide a deep well cooker structure of the above mentioned type, having improved facilities for adjusting the heater thereof to different elevations; to effect the elevational adjustment of the heater through facilities which are incorporated in the deep well cooker assembly and operatively accessible at the top of the well; to insure position raising and lowering of the heater without any angular or other displacement thereof which would cause binding or otherwise interfere with the raising and lowering of the heater; to insure a level disposition of the heater in all positions of adjustment thereof; to hold the heater securely in place in each of its positions of adjustment so that it will safely support the pot or kettle in each position; to provide a deep well cooker with several different cooking depths; to

2

provide improved facilities for supplying electric current to an elevationally adjustable electric heater of a deep well cooker; and to avoid exposure of the current supply conductors to the heat within the well; these and other objects being attained as pointed out hereafter are as shown in the accompanying drawings, in which:

Fig. 1 is a top plan view of a deep well cooker constructed in accordance with my invention and provided with an electric heater, a fragmentary portion of the range top in which the cooker is located being also shown in said figure;

Fig. 2 is a top plan view of a typical pot or cooking utensil insertable into the range well of Fig. 1;

Fig. 3 is a side elevational view of the pot of Fig. 2, the broken horizontal line about medial of the height of said pot of Fig. 3 indicating a shallower pot for which the described well is adjustable in depth;

Fig. 4 is a side view of the deep well cooker of Fig. 1 with parts broken away and in section to disclose details of constructions;

Fig. 5 is a fragmentary cross-sectional view taken substantially along the line 5—5 of Fig. 4;

Fig. 6 is a sectional view on the line 6—6 of Fig. 4 and shows the drip pan and reflector of the heating unit in section in the upper position of said unit;

Fig. 7 is an exploded side elevational view of the parts comprising the terminal structure of the heating unit whereby the current supply conductors are attached to the unit;

Fig. 8 is an end elevational view of certain connector parts of Fig. 7, looking in the direction of the arrows and along the line 8—8 of Fig. 7;

Fig. 9 is an end elevational view of the terminal block of Fig. 7 looking in the direction of the arrows and along the line 9—9 of Fig. 7; and

Fig. 10 is a plan view of the blank, in its flat form, which is bent as herein described to form the clamping member of Fig. 8.

Referring now to the drawings, the reference numeral 20 indicates a fragmentary portion of a conventional range top with an opening therethrough to accommodate a deep well cooker which extends downwardly within the range. This range top 20 is formed, around said opening, with a recessed annular set 21 which supports the deep well cooker assembly as herein-after explained.

In general, the deep well cooker assembly comprises three principal parts, namely, an outer cylindrical shell 22, a heating unit assembly which is indicated as a whole at 23, and is adjust-

able vertically in the cylindrical shell 22, and an inner cylindrical shell 24 which is located between the outer cylindrical shell 22 and the heating unit assembly 23 and movable circularly to effect the vertical adjustment of the heating unit assembly 23.

The outer cylindrical shell 22 is formed with an out-turned annular flange 25 around the top which rests in the annular seat 21 of the range top for supporting the deep well cooker assembly and said shell 22 is preferably closed at the bottom, as indicated at 26.

The inner cylindrical shell 24, which extends nearly to the bottom of the outer shell 22, has an out-turned annular flange 27 (Fig. 5) at the top overlying and secured to the inwardly extending bottom flange of an angle iron ring 28 which rests loosely on the out-turned flange 25 of the outer shell 22 whereby the inner cylindrical shell is supported for circular movement within the outer shell 22. The bottom of the inner shell 24 is preferably open and merely reinforced by an internal angle iron ring 29 to maintain the circular form thereof and at the top thereof this inner cylindrical shell 24 is provided with an inverted trough shaped ring 30 with the depending outer flange 31 thereof secured to the outer side of the upright flange of the angle iron ring 28 and the inner depending flange 32 thereof overhanging the interior of the shell 24 around the latter substantially as shown in Fig. 5.

This inverted trough shaped ring 30 extends somewhat above the range top 20 as shown in Fig. 5 and has a pair of handles 33 secured thereto, respectively at diametrically opposite places as shown in Fig. 1, and extending outwardly and somewhat upwardly therefrom as shown in Fig. 4, so that they may be manually engaged for adjusting the inner shell 22 circularly to raise and lower the heating unit assembly 23.

The cylindrical shell 24 is sufficiently smaller than the outer cylindrical shell 22 to provide an annular space therebetween to accommodate vertically extending sheet metal spacers 34 and 35 which are arranged at intervals around the inner shell 24 and permanently secured to the outer shell 22, for example by welding, and these spacers loosely engage the inner shell 24 so that the latter is free to turn concentrically within the outer shell 22. One of these spacers, namely, the spacer 35, is formed with a channel 36 providing a vertical guide for a purpose hereafter explained.

The illustrated heater assembly 23 comprises an electric heating unit 37 of a type commonly used in electric ranges wherein one or more resistances are embedded in compacted insulation in a tubular metal sheath, the particular heater herein shown being similar to that of William R. Tuttle application Serial No. 611,474, with two helical resistances 38 and a return wire 39 embedded in insulation 40 with a tubular sheath 41 of generally triangular cross section throughout its active portion as shown in Fig. 5.

This tubular sheathed heater 37 is of flat spiral form as shown in Fig. 1, with a flat top for supporting a cooking utensil thereon, and has the inner end 42 thereof closed and the outer end arranged tangentially and at downward inclination as shown at 43 in Figs. 1, 4 and 6. Both resistances 38 are connected to the return conductor 39 at the inner closed end 42 of the heater and each resistance and the return conductor

has a terminal or terminal portion at the outer end extending outwardly through the tangential portion 43 in insulated relation from one another and projecting beyond the outer end of the tubular sheath 41 as indicated at 38a, 38a and 39a in Figs. 7 and 8. Preferably the tangential portion 43 of the heater is circular in cross section for a reason hereinafter explained, instead of the triangular cross sectional form of the spiral or active portion of the heater.

This heater 37 is mounted in the top of a combination reflector and drip pan 44 which has a wide rim 45 around the top extending outwardly nearly to the surrounding inner cylindrical shell 22 within which the reflector and drip pan 44 is free to move up and down, and the wide rim 45 terminates in a down-turned marginal flange 46, as shown in Fig. 5. It is to be noted in said Fig. 5 that the diameter of the opening through the ring 30 at the top of the inner shell 22 is less than the outside diameter of the rim 45 of the pan 44 so that the ring 30 overhangs the margin of the rim 45 when the pan 44 is in the elevated position shown in Fig. 5.

The pan 44 has a bearing 47 secured thereto as at 48 and extending through its side wall in suitable tangential relation and at a suitable inclination to pivotally encircle the inclined tangential outer end 43 of the heating unit 37 when the latter is disposed in level position at the top of the pan 44, and thus provides a pivoted connection of the heater with the pan which permits the heater to be swung upwardly from its normal level portion to an upright position so as to afford access to the interior of the pan 44 for cleaning.

For supporting the heater 37 in the level utensil supporting position, the pan 44 is provided with a spider 49 upon which the heater 37 rests in the downturned closed position. This spider 49, which is shown herein as a sheet metal stamping, is preferably removable from the pan 44 and may be loosely supported therein on ledges 50 pressed inwardly from the pan wall at suitable intervals therearound to receive the outer ends of the spider arms 51 thereon.

When the heater assembly 23 is in the uppermost position of adjustment in the range well as shown in Fig. 5, wherein it serves as a surface heater, the top of the heater 37 should be above the level of the surrounding ring 30 of the inner cylinder 24 and accordingly the bearing 48 and spider 49 are located at such elevation with respect to the top of the pan 44 that in the upper position of the heater assembly, which is indicated at 23 in Fig. 4, the top of the heater 37 is slightly above the top of the ring 30 as shown in Fig. 5.

For supporting the heater assembly 23, the pan 44 has three outwardly extending brackets 52 secured thereto at intervals of about 120 degrees therearound, and each bracket has a pin 53 secured thereto which projects radially outward from the outer end of the respective bracket and carries a roller which projects through one of three similar slots 54 in the cylindrical wall of the inner shell 24.

Two of these rollers, which are indicated at 55, (Fig. 6) merely extend through the respective slots 54 whereas the other roller, which is indicated at 56, projects through its respective slot 54 and into the guideway 36 of the spacer 34 on the outer shell 22 and thereby prevents rotational movement of the heater assembly 23

while permitting elevational adjustment thereof. Each of said rollers 55 and 56 has a guide flange 57 at the inner end.

The three slots 54 are alike and arranged at 120 degree intervals around the inner shell 24 and extend substantially spirally as shown in Fig. 4 so that when the inner cylindrical shell 24 is rotated, said slots, by their engagement with the rollers 55 and 56 of the non-rotatable heater assembly 23, raise or lower said assembly in the well structure, depending upon the direction of rotation of the inner shell 24.

Thus by proper extent of rotation of the inner shell 24, the heater assembly 23 may be adjusted to any selected elevational position within the well structure.

However, as the elevational adjustment of the heater assembly 23 may not be sufficiently secure in some cases when the rollers 55 and 56 are supported on spiral or inclined positions of the slots 54, especially when a heavy load is supported on the heater 31, and the heater assembly might become accidentally displaced from the selected elevated position, I prefer to provide the slots 54 with formations which will positively hold the heater assembly at those elevations where it is generally desired to adjust the assembly in the well.

Thus each slot 54 is provided at its upper end with a horizontal extension 58 in which the respective rollers 55 and 56 engage when the heater assembly is elevated to its uppermost position in the well, as shown in Fig. 5 and at 23 in Fig. 4, wherein the heater 31 is positioned to be used as a surface heating unit. Inasmuch as the bottom supporting edges of the slot extensions 58 are horizontal, the heater assembly 23 has no tendency to become displaced from the elevated position and is thus safely retained in that elevated position.

No such safeguarding means is required at the lower end of the slot 54 to prevent such accidental displacement of the heater assembly from the lowermost position, indicated at 23a in Fig. 4, in the well, but it is preferred to provide each slot 54 at the lower end also with a horizontal extension 59 in which the rollers 55 and 56 engage when the heating assembly is in the lowermost position 23a in the well.

Generally, for deep well cooking, the heater is positioned at the bottom of the well and a pot or kettle is employed, such as shown at 60 in Fig. 3, of such length that it rests on the heater at the bottom of the well, but in some cases it may be desirable to employ a shallower pot or pan, such as indicated at 61 in Fig. 3, or substantially half the depth of the well.

In order to retain the heating assembly 23 at the half way elevation, indicated at 23b in Fig. 4, each slot 54 is correspondingly offset intermediate of its length to provide a horizontal portion 62 for supporting the rollers 55 and 56 at the half way level to prevent accidental displacement of the heating assembly 23 at the intermediate position 23b. This horizontal offset 67, has an appreciable effect in the raising and lowering operation of the heater whereby the half way level is readily ascertained.

From the foregoing it will be understood that when the heater assembly 23 is in the bottom position 23a, it may be readily adjusted from that position to the top position, indicated at 23 in Fig. 4, by merely grasping the handles 33 and rotating the inner shell 24 in a clockwise direction to the full extent of its turning movement, and

that rotation of said shell 24 in a counterclockwise direction will return the heater assembly to the bottom position 23a. Moreover, by rotating the shell 24 to the position substantially half way between the extremes of its rotary movement the rollers 55 and 56 will be engaged on the central offsets 62 and the heater assembly thus securely held in the position 23b midway between the top and bottom of the well.

10 The pot used with this deep well cooker preferably has a pair of handles 63 pivoted thereto so that they normally lie flat and may be turned upwardly for conveniently lifting the pot and also to permit convenient movement of the handles 33 past these handles 63.

15 The tangential outer end 43 of the heating unit 31 is of such length to project outwardly through the shells 24 and 22 to the exterior of the latter and the outer shell 22 is accordingly provided 20 with a vertical slot 64 through which said end 43 extends and of suitable length to permit the necessary vertical movement of said end 43 in the vertical adjustment of the heater assembly 23 in the well.

25 The inner shell 24 also has a slot through which said heater end 43 extends, said slot which is indicated at 65, being of the same spiral form as the slots 54 and with horizontal end extensions corresponding to the end extensions 58 and 30 59 of the slots 54 and with a midway horizontal offset 66 corresponding to the midway offsets 62 of the slots 54 so as to permit free vertical movement of said heater end 43, corresponding to that of the heater assembly 23, as the inner shell 24 is rotated.

35 Current is supplied to the heating unit 31 through flexible conductors which are connected to the terminals 38a and 39a of the heating unit at the out end of the tangential portion 43 thereof through a fitting which is applicable to the outer end of said portion 43 after the heating unit is installed in the well.

40 The fitting comprises a terminal block 67 of insulating material, for example, porcelain, which is secured on the end of the portion 43 by a clamp 68 which encircles the outer end of the portion 43 and is clamped thereon by a clamping bolt 69. This clamp may be conveniently made from a sheet metal blank such as shown at 70 in Fig. 10, which is doubled over to provide a fold 71 in which the clamping bolt 69 is located, and has a ferrule 72 secured on the outer side thereof to receive a neck portion 73 of the terminal block 62. This neck portion 73 is notched at 74 for engagement by a pin 75 passed through openings 76 of the ferrule 72 to secure the neck portion 73 in the ferrule 72.

45 The terminal block 67 has three connections 77, recessed therein, to which the three terminals 38a, 38a, and 39a of the heating unit 31 are attached respectively and to which the flexible current supply conductors above mentioned are connected. One of these conductors is shown at 78 in Fig. 4.

50 While I have shown and described my invention in a preferred form, I am aware that various changes and modifications may be made therein without departing from the principles of my invention, the scope of which is to be determined by the appended claim.

55 70 What is claimed is:
75 In a deep well cooker of the class described, the combination of a range top having an opening therethrough, a double walled well enclosure extending downwardly from said open-

ing and composed of inner and outer cylindrical walls, the outer cylindrical wall being suspended at its upper end from the range top and held thereby against rotation, and the inner cylindrical wall being rotatably mounted within the outer cylindrical wall, and a heater which is located within and raised and lowered by rotation of the inner cylindrical wall, said inner wall having a plurality of corresponding spiral slots therethrough and equally spaced therearound and said heater having radial extensions therearound and being supported by engagement of said extensions in said spiral slots, said outer wall having on the inner face thereof a vertical channel into which one of said extensions projects.
